E.R. Nowlan Atty.

UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed November 26, 1920. Serial No. 426,487.

To all whom it may concern:

Be it known that I, CHARLES L. GOODRUM, a citizen of the United States, residing at New York, in the county of New York, State of New York, have invented certain new and useful Improvements in Telephone-Exchange Systems, of which the following is a full, clear, concise, and exact description.

10 This invention relates to telephone exchange systems and particularly to systems in which means is provided for giving supervision of talking connections established through the agency of machine switching apparatus.

15 There exists a wide variation in the different types of talking connections that may be established between subscribers' lines in an exchange system. This is especially true in the case of an exchange comprising a plurality of central offices located at various distances from each other. Certain connections may be for the purpose of uniting a calling subscriber's line with a called subscriber's line in the same central office. Other connections may be extended to subscribers' lines in an adjoining office, while still others may lead over interoffice trunks through a plurality of offices in the system to a distant point. These different classes of connections often provide a convenient and logical standard on which to base the rates of assessment made against the telephone subscribers for the service rendered.

20 For example, subscribers will be permitted to make calls to lines local to their own office and also perhaps to nearby offices, where only short trunks are necessary, for the fixed flat rate of charge. On distant calls, however, involving the use of long and expensive trunk lines, an additional assessment is made against the calling subscriber's line for each such connection he establishes.

25 Where certain offices are provided with private branch exchanges it is desirable to give the subscribers to these exchanges the same privileges as the subscribers to central office lines in obtaining the various classes of connections above enumerated. If the private branch exchange is one that is

equipped with machine switching apparatus for extending calls to the central office it becomes necessary to provide some means for notifying an operator or attendant in the branch exchange of the class of the call being made.

With the foregoing conditions in mind it is the object of this invention to provide, in a system where connections are established over multi-position selective switches, means for causing the actuation of a signal device, when one of said switches is selectively operated to certain of its positions, to give a notification of the class of the call that is being extended.

A feature of the invention relates to the provision of means for actuating a signal device when one of the selective switches used in the extension of a connection is operated to select certain ones of a plurality of groups of outgoing trunks.

A further feature relates to the provision of a signal lamp at an operator's or attendant's position which is lighted, when one of the selective switches is operated to select certain ones of a plurality of groups of trunks, to advise the operator of the nature of the call that is being extended.

Other features will appear from the detailed description given hereinafter and from the appended claims.

Referring to the drawing which forms a part of this application, the figure illustrates a portion of a telephone exchange system showing in sufficient detail the circuits and apparatus constituting the subject matter of the invention. To the left of the vertical broken line in the figure is shown a subscriber's telephone line terminating in the multiples of an automatic switch in a private branch exchange. Furthermore, certain of the automatic switches in the private branch exchange are illustrated diagrammatically together with one of the trunk circuits outgoing to the central office. To the right of the vertical line the central office is shown provided with an automatic selector switch in which terminates the trunk line incoming from the private branch exchange.

The automatic switches shown diagram-

matically in the private branch exchange may be of any desired character, but are preferably two movement step-by-step switches of the well-known type. The automatic selective switches installed at the central office, the circuit diagram of one of these switches being shown in detail in the figure, may likewise be step-by-step switches of any suitable and approved type. The particular switch shown in this disclosure is of the so called "around and up" type. In the primary movement of the switch the brush shaft is rotated to position one of a plurality of sets of brushes in operative relation to a desired group of terminals. In the second movement of the switch the brush shaft is stepped vertically to drive the selected set of brushes over the terminals of the contact bank. The structural details of such a switch are illustrated and explained in full in the patent to Forsberg, No. 1,252,420, issued January 8, 1918.

The subscribers to the private branch exchange are afforded the privilege of making calls to lines local to their own central office and also to distant subscribers' lines which must be reached by means of interoffice trunk connections. Whatever class of call the private branch exchange subscriber wishes to make, he first extends his line automatically, by means of a dial such as shown at 101, through a selector switch at the private branch exchange which selects an idle trunk 121, 122 outgoing to the central office. The connection having been extended to an incoming switch at the central office, the next digit or digits will determine the positioning of the switch or switches in the central office to route the call either to a local subscriber's line or to an interoffice trunk, as the case may be. In the case of a local call the first group selector in the central office will be operated to select the proper one of a plurality of groups of trunks, such as the group illustrated at 150. An idle trunk is then selected in this group and the extension of the connection continued to select a called subscriber's line. On an interoffice call, however, the first group selector will be operated to choose the proper one of a plurality of different groups of trunks, one of which groups is illustrated at 140. The hunting movement of the switch thereafter chooses an idle trunk in this group and the connection is extended to the distant office.

The detailed operation involved in the establishment of the connection will next be considered. For this purpose assume that the subscriber at substation 100 in the private branch exchange wishes to obtain a connection with a subscriber's line local to the central office illustrated at the right of the figure. On removing the receiver from the switchhook at substation 100 an

automatic line finder switch, the brushes of which are shown at 105, 106 and 107, is started in operation to find the terminals 102, 103 and 104 of the calling line. Thereafter the calling subscriber manipulates his impulse transmitter 101 to send a series of impulses corresponding to the first digit in the wanted number. This series of impulses causes the primary operation of the first selector switch, the brushes of which are shown at 108, 109 and 110. Following the group selecting movement of the first selector switch the brushes 108, 109 and 110 are driven automatically to search and make connection with the terminals 111, 112 and 113 of an idle trunk 121 and 122 outgoing to the central office.

The following circuit may now be traced for the energization of the line relay 115 associated with the outgoing trunk: Battery, right-hand winding of said relay, lower left-hand winding of repeating coil 114, terminal 112, brush 109, brush 106, terminal 103, through the loop of the calling substation 100, terminal 102, brush 105, brush 108, terminal 111, upper left-hand winding of repeating coil 114, left-hand winding of relay 115 to ground. Relay 115 becomes energized and closes a circuit from battery through the winding of relay 116, front contact and left-hand armature of relay 115 to ground. Relay 116 becomes energized in this circuit. Relay 115 also completes a circuit as follows for the impulse relay 125 at the incoming selector switch in the central office: Battery, through the right-hand winding of relay 125, side switch arm 124 (position 1), conductor 122, lower right-hand winding of repeating coil 114, contact and right-hand armature of relay 115, winding of relay 120, upper right-hand winding of repeating coil 114, conductor 121, side switch arm 123 (position 1), left-hand winding of relay 125 to ground. It may be noted that the instant that the relay 115 attracts its armature a circuit is momentarily closed from battery through the winding of relay 118, right-hand normal contact of said relay, armature and contact of relay 117, contact and armature of relay 120, front contact and left-hand armature of relay 115 to ground. Relay 118 is constructed to attract its armatures slowly, and, therefore before it can become energized the relay 120 operates in series with relay 125 to open the circuit just traced for relay 118. Relay 118 consequently does not become energized at this time. Relay 116, at its right-hand armature and contact, closes a circuit for the application of ground potential to the test terminal 113 of the outgoing trunk in order to render this trunk non-selectable to other switches in the private branch exchange.

When relay 125 operates it completes a

circuit from battery through the winding of relay 126, front contact and armature of relay 125 to ground. Relay 126 becomes operated in this circuit and prepares a circuit for the primary stepping magnet 129. The calling subscriber, operating his impulse transmitter 101, sends out a series of impulses corresponding to the next digit of the called number. On the first interruption of the line circuit relay 115 releases its armatures and opens the circuit of relay 116. This relay, however, being slow-to-release does not deenergize in the brief interruptions of its circuit during the transmission of a series of impulses. Relay 115 closes a circuit from ground through its left-hand armature and back contact, left-hand armature and contact of relay 116, winding of relay 117, to battery and ground. Relay 117 becomes energized and being of the slow-to-release character remains operated during the following impulses of the series. Relay 117, at its armature and contact, maintains open the operating circuit of relay 118.

Relay 115, at its right-hand armature and contact, opens the circuit of relay 120 and the impulse relay 125 at the central office. Relay 125, on deenergizing, completes a circuit from ground through its armature and back contact, left-hand armature and contact of relay 126, off normal contact 154, winding of primary stepping magnet 129, to battery and ground. In parallel thereto a circuit is also completed through the winding of the slow-to-release relay 127 to battery and ground. Relay 127, at its armature and contact, closes a circuit for the energization of the escape magnet 128. The escape magnet 128 operates and prepares to release the side switch into position 2 when the energizing circuit of said magnet is opened. The primary stepping magnet 129 operates to advance the set of brushes 133, 134 and 135 through one rotary step. When the line circuit closes at the end of the first impulse relay 115 attracts its armatures and completes the energizing circuit for relays 125 and 120. Relay 125 opens the circuit of stepping magnet 129 and relay 127 and recloses the circuit of slow-to-release relay 126. Relay 127 remains energized while the stepping magnet 129 releases its armature. When relay 126 first energizes it completes a circuit from battery through the winding of relay 132, contact and right-hand armature of relay 126 to ground. Relay 132 becomes energized and remains energized as long as relay 126 holds its armatures attracted.

For each succeeding impulse of the series the magnet 129 drives the set of brushes through one rotary step finally bringing them to rest in operative relation to the group of trunks 150 containing the trunk

151, 152 and 153. During the primary rotary movement of the switch, the group brush 142, attached to the brush shaft, is rotated from one segment to another. The brush 142 is so attached to the brush shaft 70 as to participate in the rotary movement of the shaft but remains in the same horizontal plane during the secondary or vertical motion of said shaft. It will be observed that a circular row of ten terminals 75 are provided for the group brush 142. Each of these terminals corresponds and is individual to a group of trunk terminals. Since it was assumed that the call being extended was one for a local subscriber's line, the 80 group brush 142 at the end of the movement of the switch is standing on some one of the group terminals other than terminals 143, 144 and 145, which are shown connected to the conductor 155.

After an interval has elapsed following the transmission of the last impulse, relay 125 remains energized long enough to permit the release of slow relay 127. Relay 127 opens the circuit of the escape magnet 128 which immediately deenergizes and advances the brushes 123, 124, 141, 146, 149 and 157 of the side switch to their second position terminals. In this position of the side switch the escape magnet 128 is immediately energized in a circuit from battery through the winding of said magnet, arm 146 (position 2), off normal contact 147 to ground. Magnet 128 operates preparatory to releasing the side switch into its third position upon deenergization. Also a circuit is established from battery through the winding and contact and armature of the secondary stepping magnet 130, arm 149 (position 2), front contact and armature of relay 125 to ground. The stepping magnet 130 energizes, interrupts its own circuit and advances the brushes 133, 134, and 135 to the first set of terminals in the selected group 150. As the brush shaft takes its first vertical step the off normal contacts 147 and 154 are opened. Contact 147, however, does not open until shortly after the test brush 135 has made engagement with the test terminal of the first trunk. Hence, if the first trunk in the group is busy a ground potential will be present on the test terminal 153 and a circuit is completed as follows for maintaining the energization of the escape magnet 128: Battery, through the winding of said magnet, arm 146 (position 2), test brush 135 to the grounded test terminal 153. The side switch remains in position 2 and the stepping magnet 130 continues to advance the brushes until the first idle trunk in the group is reached. At this time the escape magnet 128 becomes deenergized and advances the side switch from its second to its third position. Side switch arm 149 in leaving position 2 opens the cir-

cuit of the stepping magnet 130 to prevent any further operation of the switch. The test terminal 153 is immediately rendered busy to prevent selection by other switches by means of the following circuit: Ground through the right-hand armature and contact of relay 126, side switch arm 157 (position 3), side switch arm 146 (position 3), brush 135 to the multiples of terminal 153.

10 The side switch on passing out of position 2 opens, at its arms 123 and 124, the circuit including the winding of relay 125 and relay 120 in the private branch exchange. These relays immediately become deenergized. After an interval has elapsed the slow-to-release relay 126 also releases its armatures. The release of relay 126 removes the ground, which up to this time has afforded a holding circuit for relay 132 and 15 also served to render the test terminal 153 of the selected trunk temporarily busy. Before the relay 126 has had time to deenergize, however, a ground potential is supplied from the succeeding switch to maintain the trunk busy and also to hold the relay 132 energized. The manner in which this ground potential is applied to the test terminal 153 from the succeeding switch before the slow-to-release relay 126 has had 20 time to deenergize is shown and described in the patent to Clausen, No. 1,340,933, issued May 25, 1920.

From this point on the extension of the call is continued under the control of the 25 calling subscriber, and as many succeeding switches are operated as are necessary to extend connection to the called subscriber's line.

At the termination of the conversation 30 the called subscriber, by replacing his receiver on the switchhook, brings about the release, in any well-known manner, of the switches succeeding those shown in the drawing. The release of the next succeeding 35 switch causes the removal of ground potential from the test terminal 153 and the resultant deenergization of relay 132. The release of relay 132 causes the closure of a circuit from battery through the winding of 40 release magnet 131, primary off normal contact 148 contact and armature of relay 132 to ground. Magnet 131 energizes and locks up in a circuit through its contact and armature and the off normal contact 148. The 45 brushes 133, 134 and 135 are restored to their normal position at which time the contact is opened and the release magnet 131 becomes deenergized. The calling subscriber, by replacing his receiver to the 50 switchhook, brings about the release of the automatic switches in the private branch exchange.

A case will next be considered in which 55 a subscriber in the private branch exchange wishes to obtain a connection with a sub-

scriber's line in a distant office, necessitating the use of an interoffice trunk interconnecting such distant office with the central office illustrated in the drawing. The operation of the apparatus in the private branch exchange takes place in the manner already described. The digit of the called number instrumental in the group selecting movement of the automatic switch in the central office differs in the present case, however, 70 from the corresponding digit of the number previously considered. The result is that the brush shaft of the selector switch carrying the brushes 133, 134 and 135 is rotated to select one of a plurality of groups of 75 trunks, such as the group 140, leading to the desired distant office. As shown, the selector switch is equipped with three such groups of trunks which correspond to the group terminals 145, 144 and 143. Obviously, 80 as many interoffice trunk groups as desirable could be provided.

Since the brushes 133, 134 and 135 at the end of the primary movement of the switch are standing in operative relation to a group 85 of interoffice trunks leading to a distant office, the group brush 142 is in engagement with one of the groups of terminals, such as terminal 145, connected to the conductor 155. Therefore, when the slow-to-release 90 relay 127 becomes deenergized, following the series of impulses, and the escape magnet 128 operates to advance the side switch into the second position, a circuit is closed as follows to shunt out the relay 120 at the 95 private branch exchange: Battery through the right-hand winding of relay 125, conductor 155, terminal 145, brush 142, side switch arm 141 (position 2), left-hand winding of relay 125 to ground. Relay 120 in 100 the private branch exchange deenergizes and completes a circuit from battery through the winding and normal contact of relay 118, armature and contact of relay 117, contact and armature of relay 120, 105 front contact and left-hand armature of relay 115 to ground. It will be noted that the slow-to-release relay 117 becomes deenergized following the lapse of the necessary 110 interval after the transmission of the series 115 of impulses. The relay 118 operates and closes a holding circuit for itself from battery through its winding, make before break contact and right-hand armature to ground at the contact and right-hand armature of 120 relay 116. Relay 118, at its left-hand armature, closes a circuit for the signal lamp 119. The attendant at the private branch exchange, observing the illumination of the lamp at 119, knows that some subscriber 125 is making a central office call of the class that requires an additional charge. She thereupon depresses her listening key 159 which places her head set in talking relation with the calling line. By inquiring 130

from the calling subscriber the attendant learns of the nature of the call being extended and thereby determines the necessary charge to be made against the calling line in case the desired call proves successful. After having learned all the necessary information for determining the additional charge to be made, the attendant releases listening key 159 and retires from the connection.

10 Returning to the point where the group selector in the central office had completed its group selecting movement and the escape magnet had released the side switch into the second position, it may be noted that from here on the extension of the connection progresses in the manner similar to that described in detail hereinbefore. The circuit of the secondary magnet 130 is closed and the brushes 133, 134 and 135 are elevated vertically to select an idle trunk 136, 137 and 138 in the interoffice group 140. The brush shaft takes its first secondary step immediately that the side switch reaches position 2, but since the brush 142 does not disengage the terminal 145 during the vertical movement of the switch the shunt around the winding of relay 120 is maintained for a period to insure the operation of the slow to energize relay 118 in the private branch exchange. After an idle trunk has been found the side switch advances into position 3 and the circuit of relay 125 is opened as arm 141 leaves its second position terminal. From this point on the further extension and release of the interoffice connection may take place in any well-known manner.

What is claimed is:

1. In a telephone exchange system, a connecting circuit, a multi-position selective switch having primary and secondary movements, means for extending a talking connection over said circuit to the selective switch, means for operating said switch to any one of its positions, a signal, actuating means controlled over said connecting circuit for actuating said signal, and means operated when the selective switch is moved to certain of its positions for rendering said actuating means effective.
2. In a telephone exchange system, an office, a second office, a trunk circuit interconnecting said offices, a multi-position selective switch at the second office, means for extending a talking connection over said trunk circuit to the selective switch in the second office, means for operating said switch to any of its positions, a signal in said first office, means controlled over said trunk circuit for actuating said signal, and means operated when the selective switch is moved to certain of its positions for rendering said actuating means effective.
3. In a telephone exchange system, an office, a second office, a two-wire trunk circuit

interconnecting said offices, a multi-position selective switch at the second office, means for extending a talking connection over said trunk to the selective switch in the second office, means for operating said switch to any of its positions, a signal in said first office, means controlled over said trunk circuit for actuating said signal, and means operated when the selective switch is moved to certain of its positions for rendering said actuating means effective.

4. In a telephone exchange system, a trunk circuit, a multi-position selective switch having primary and secondary movements, means for extending a talking connection over said trunk to the selective switch, means for operating said switch to any one of its positions, a signal, means operated when said switch is moved to certain of its positions for changing the electrical condition of said trunk, and means responsive to said change for actuating said signal.

5. In a telephone exchange system, a connecting circuit, a multi-position selective switch having primary and secondary movements, means for extending a talking connection over said circuit to the selective switch, a plurality of groups of trunks to which said switch has access, means for operating said switch to select any one of said groups of trunks, a signal, means controlled over said connecting circuit for actuating said signal, and means operated when said switch is moved to select certain of said groups of trunks for rendering said actuating means effective.

6. In a telephone exchange system, an office, a second office, a trunk circuit interconnecting said offices, a multi-position selective switch in said second office, means for extending a connection over the trunk circuit to said switch, means for operating said switch to any one of its positions, an operator's position at the first office, a signal lamp at the operator's position, means operated when the selective switch is moved to certain of its positions for changing the electrical condition of said trunk at said second office, and means at the first office responsive to such change in condition for rendering the signal lamp at the operator's position effective.

7. In a telephone system, a private branch exchange, a main office, a trunk circuit terminating at one end in said private branch exchange and at its other end in said main office, a signal for said trunk at the private branch exchange, an operator's telephone set thereat, a selector associated with said trunk at the main office, groups of trunks terminating in said selector and leading to distant and local offices, a subscriber's line at said private branch exchange, a sender thereat, a switch controlled thereby for extend-

ing the subscriber's line to said trunk and for then operating the said selector to select a group of said trunks, means operated only when a trunk group to a distant office is selected for operating said signal, and means controlled by the operator at the private branch exchange for connecting her

telephone set with the trunk to supervise the connection.

In witness whereof I hereunto subscribe ¹⁰ my name this 20th day of November, A. D., 1920.

CHARLES L. GOODRUM.
